UNITED STATES PATENT OFFICE.

HAROLD D. GRINNELL, OF PITTSFIELD, MASSACHUSETTS, ASSIGNOR TO THE G. C. A. MANUFACTURING COMPANY, OF PITTSFIELD, MASSACHUSETTS, A CORPORATION OF MASSACHUSETTS.

LAMP-BULB INSTALLING AND REMOVING DEVICE.

Application filed May 22, 1922. Serial No. 562,684.

To all whom it may concern:

Be it known that I, HAROLD D. GRINNELL, a citizen of the United States, and a resident of Pittsfield, in the county of Berkshire and State of Massachusetts, have invented an Improvement in Lamp-Bulb Installing and Removing Devices, of which the following description, in connection with the accompanying drawings, is a specification, like characters on the drawings representing like parts.

This invention relates to apparatus for installing and removing incandescent lamp bulbs, and aims to provide novel and improved means for manually performing these operations quickly and safely, and particularly in respect to lamps suspended from cords or other non-rigid supports and mounted in elevated position beyond the grasp of the operator.

My invention will best be understood from a description of a specific useful embodiment thereof, illustrated in the accompanying drawings, wherein:

Fig. 1 is a front elevation of the device shown in operative relation to an incandescent lamp of the usual type, the same being illustrated in connection with an ordinary form of lamp shade, an auxiliary attachment for supporting the lamp socket being shown in the closed position;

Fig. 2, a view similar to Fig. 1 and illustrating the lamp socket engaging means in operative position, the lamp shade shown in Fig. 1 having been removed and the clamping arms for gripping the same being shown in the folded position;

Fig. 3, a detail cross-sectional view on the line 3—3 of Fig. 2;

Fig. 4, a detail perspective bottom view of the outer or extension portion of the lamp socket supporting attachment; and

Fig. 5, a detail vertical section of the clutch illustrated in operative relation to a lamp bulb.

Referring to the accompanying drawings, it will be observed the present device comprises a lamp bulb engaging portion, a lamp shade engaging portion, and a lamp socket engaging portion all mounted upon a common support or rod, each of said portions being separate and arranged for cooperative relationship with one or both of the remaining portions. This rod is of indefinite

variable length and adapted to enable the operator to conveniently manipulate an object when placed beyond his grasp. The rod may be formed in any manner suitable to the purpose, and is preferably composed of a series of sections detachably connected so that by adding or removing a suitable number their aggregate length may be readily accommodated to the required reach for operation.

As herein shown, the rod comprises permanent upper and lower tubular sections 10, 11, jointedly connected as at 12 in any suitable manner, the upper end of the rod being fitted with a fixed head 13 seated within the tubing and having an exposed portion extending beyond the rod, while the opposite end of the rod carries a handle 14 having a reduced portion 15 extending slidably into its interior a distance preferably at least equal to the limits of movements of the handle, as hereinafter described.

The head 13 is provided with a central bore to receive a sliding spindle 16 formed in sections which are jointedly connected at convenient points and correspond in length to the rod sections through which they extend so that they may be detached therewith, the lowermost spindle section being seated in the upper end of the reduced portion 15 of the handle.

The spindle 16 is extended upward through and beyond the head 13 and carries at its upper extremity a detachable socket member 17 adapted to support a removable clutch 18 for receiving a lamp bulb 19.

The socket member 17 has a depending stem 20 provided centrally with a suitable bore or recess to receive the upper extremity of the spindle 16, being removably secured in fixed position, as by a set-screw 21. In the upper end of the socket member 17 is a circular well 22 having inclined side walls corresponding with the formation of a stem 23 provided on the clutch 18 and adapted to seat firmly therein the object of this construction being to removably seat the clutch rigidly in the socket member with sufficient firmness to prevent relative movement therein when the clutch is subjected to rotative action administered by the operator when inserting or removing the lamp bulb.

The clutch 18 is a hollow receptacle hav-

ing the formation of an inverted frustum, the large end being open to receive a lamp bulb and the lower end being closed by a perforate bottom 24 suitably secured thereto and depending centrally from which is the stem 23 above referred to. The side walls of the clutch are preferably constructed of flexible material, such as paper, rubber or thin sheet-metal, having the requisite properties to grip and bind upon the surface of the lamp bulb, conforming to irregularities in the surface or outline thereof.

Pivoted at their lower ends to the exposed portion of the head 13 of the rod by any suitable means, such as the screws 25, 25, are a pair of oppositely arranged adjustable clamping arms 26, 26, adapted to swing at their outer ends toward and away from each other for gripping a lamp shade 27, the lamp shade herein illustrated (Fig. 1) being detachably supported in the usual manner upon a bracket 28 carried on the lamp socket 29 into which the bulb 19 is screwed, said shade forming a dependent skirt freely surrounding the bulb.

In the present embodiment the arms 26, 26, are constructed of metal tubing, each being provided at its lower end with a bifurcated portion 30 arranged to straddle the head 13 and secured thereto in the manner above indicated. Slidably mounted in the outer end of each of the clamping arms is an adjustable arm extension member 31 carrying in turn at its outer extremity a fixed clamp for seating and gripping the lamp shade 27. These clamps are of open structure and preferably constructed of sheet metal suitably formed and shaped to provide a lower transverse portion or rest bar 33 arranged to extend under and engaging the lower rim of the lamp shade, and a separate upper transverse portion or bearing bar 34 outwardly offset from the lower portion and curved lengthwise to conform to the normally rounded contour of the lamp shade against which it bears at a point above the rim, said rest and bearing bars being rigidly held in spaced relation by connecting struts 35 at each end and preferably provided with a protective covering 36 of tape or other suitable material, the space intervening said rest and bearing bars being adapted to receive a segment of the shade rim.

The clamping arm extension members 31, 31, are adjustable to any desired elevation and preferably secured in a given position by means of a threaded stud 37 laterally carried by each of said members and arranged to slide in a suitable slot (not shown) provided lengthwise in the wall of each clamping arm, the outer end of each stud being fitted with a nut 38.

The clamping arms 26, 26, are pivotally secured to the spindle 16 by braces 39, 39,

each of which is attached at its outer end preferably to eye members 40 struck up centrally from the clamping arms, and at its outer end to an apertured yoke 41 slidably mounted in horizontal position on the spindle 16 above the rod 10 and provided terminally with suitable eyes for attachment to the braces 39.

The clamping arms 26, 26, are normally held in the closed position by a coil expansion spring 51 mounted on the spindle 16 above the rod 10, said spring bearing at its lower end against the head 13 and at its upper end against a sliding collar 43, which is preferably interposed between the spring 51 and the yoke and adapted to operate as a spacing member to spread the braces 39, 39 to insure their proper angular relation in the closed position.

Pivotedly secured at its inner end to the rod 10, and preferably immediately below the point of attachment of the clamping arms, is an auxiliary supporting arm 42 including a jointed extension portion 43, the arm 42 being adjustably secured to a wing collar 32 detachably held in position by bolts 45, 45, carrying suitable thumb-nuts. This portion of my device is designed to cooperate with the clutch portion for removing the lamp bulb and may be used independently of or in combination with the clamping arms 26, 26; that is to say in every instance where the lamp bulb is suspended from a cord or other non-rigid support and no lamp shade is carried on the socket 29 to which the clamping arms may be applied to provide the necessary support, and also in those instances where a lamp shade is employed but either it or the shade supporting bracket 28 is found to be loose or too infirm to afford the requisite degree of strength and rigidity then the auxiliary arm may be employed to advantage. To this end and for adaptation to a lamp socket with or without a lamp shade the said supporting arm is constructed of separate pivotally connected portions 42, 43 adapted to assume angular relation with respect to each other when in the open position and of sufficient length to admit lamp shades of different sizes and formation, the outer extremity of the outer or extension portion 43 being provided with a hollow receptacle 44 of frusto-conical formation adapted to enclose the lamp socket 29, a sectoral portion of the receptacle being removed to provide a suitable space 50 to receive the cord 46 and the switch key 47 of the socket. The inner and outer portions 42, 43 of the supporting arm are preferably connected by a transverse bolt 48 carrying a suitable wing nut for fixing the relative positions of these parts, the correct angular adjustment of the outer portion in the open position being determined preferably by an abutting shoulder 49 carried on the outer

extremity of the inner arm 42. When not in use, the supporting arm is adapted to assume the closed position illustrated in Fig. 1 wherein the parts 42, 43 are folded together in vertical position adjacent the rod 10.

When my device is applied to a lamp of the character indicated in combination with a lamp shade, the operator grasps the rod firmly in an upright position in one hand 10 and pulls down upon the handle 14 with the other hand, this action bringing the clutch socket member 17 into engagement with and depressing the yoke 41 against the yielding opposition of the spring 51 and 15 causing the clamping arms 26 to spread an appropriate distance to receive the lamp shade. Downward pull on the handle 14 is then discontinued and the clamps are forced into gripping and supporting engagement 20 with the shade, responsive to the action of the spring 51, as illustrated in Fig. 1. Preliminary adjustment of the clamping arm extension portions 31, 31 in the manner before indicated may be necessary to give the 25 clamping arms the required reach and to permit sufficient space between the lamp socket and the lower limit of movement of the clutch 18 for play of the latter in installing or removing the lamp bulb. The 30 spindle 16 being now free to be raised without disturbing the position of the clamping arms, the clutch 18 is forced upward over the outer or enlarged end of the bulb and at the same time sufficient downward pull is 35 exerted by the operator upon the clamping arms to hold the lamp shade and therewith the lamp bulb in stationary position. When the bulb is well seated in the clutch the 40 spindle 16 is then rotated to unscrew the bulb from its socket, after which the clamping arms are again spread in the manner above described for disengaging the lamp shade. Similar operations, involving the 45 reverse action of the spindle 16, may be employed to install the bulb in the socket.

As the clutch is removable in its mounting, it will be understood that any one of a series of clutches having like-sized stem portions but well portions of different capacities may be employed.

In case there is no lamp shade to which the clamping arms may be applied to afford the necessary rigidity to the lamp socket during the operations above referred to, or in case the shade, when employed, is insufficiently rigid for supporting purposes, I then bring into requisition the auxiliary attachment consisting of the supporting arms 42, 43. These arms are then positioned as shown in Fig. 3, the receptacle 44 being placed over and enclosing the lamp socket 29, for which purpose the marginal opening 50 is made of sufficiently ample proportions to freely admit the lamp cord 46 and key 47. The slight downward pressure exerted

upon the rod 10 above referred to being also effective to prevent upward displacement of the lamp socket and bulb.

It will be apparent that my invention is not restricted to the particular embodiment 70 herein shown and that obvious modifications in the structure, combination and arrangement of its parts may be made without departing from the objects of the invention.

I claim as my invention:

1. In a device of the class described, in combination, a support, means for holding a lamp bulb, means for holding the lamp shade and means for holding the lamp socket, all mounted in cooperative relationship on said support. 80

2. In a device of the class described, in combination with a support, separate cooperative gripping mechanisms carried by the support, one of said mechanisms being adapted to grip the lamp bulb and the other of said mechanisms being adjustable on its mounting and adapted to grip the lamp socket. 85

3. In a device of the class described, in combination, a support, means for gripping a lamp bulb, and means for securing said support to a plurality of objects independently of the lamp bulb. 90

4. In a device of the class described, the combination with a support and gripping means carried by the support for engaging and disengaging a lamp bulb, of cooperative means for securing the lamp socket in stationary position, said cooperative securing means having an adjustable angle in its length. 95

5. In a device of the class described, in combination, a support, a clutch, means for controlling the clutch to engage and disengage a lamp bulb, and an adjustable gripping arm carried by the support effective to hold the lamp socket in relatively stationary position during operations on the lamp bulb. 100

6. In a device of the class described, in combination, a support, a turning member mounted to slide within the support and extending beyond one end of the support, means carried on said extended portion of the turning member for gripping a lamp bulb, and a collapsible arm pivoted at one end to the support and carrying at its opposite end means effective to secure the lamp socket in stationary position. 115

7. In a device of the class described, in combination with a support and means carried by the support for engaging and disengaging a lamp bulb, of an adjustable arm pivoted at one end to said support and carrying means at its opposite end for engaging the lamp socket, and means for fixing the position of the arm relatively to the support. 120

8. In a device of the class described, in combination, a support, means carried by the 130

support for engaging and disengaging a lamp bulb, an arm pivoted at one end to said support and carrying at its opposite end a receiving member for gripping the lamp socket, said arm having a plurality of movably connected sections adapted to form an angle in its length.

9. In a device of the class described, in combination with a support and means carried by the support for engaging and disengaging a lamp bulb, of an arm pivoted at one end to said support, and carrying at its opposite end means for securing the lamp socket in stationary position, said arm being formed of jointedly connected sections adapted to be opened and closed, and means for controlling the angular relationship of said arm sections in the open position.

10. In a device of the class described, in combination, a support, a thrust member

mounted to slide within said support and extending beyond one end of the support, means carried on the thrust member for gripping a lamp bulb, clamping arms pivoted at their lower ends to the support and having their opposite ends free to be swung toward and away from each other beyond the support, a sliding member carried on said extended portion of the thrust member, braces pivotally connecting the clamping arms with said sliding member, spacing means for limiting the inward movement of the braces, and means for actuating the clamping arms into the closed position for gripping an object independent of the lamp bulb.

In testimony whereof, I have signed my name to this specification.

HAROLD D. GRINNELL.
